UNITED STATES PATENT OFFICE.

JOHN DENNIS, OF GLENBEULAH, WISCONSIN.

COMBINED WASH-BENCH AND WRINGER.

SPECIFICATION forming part of Letters Patent No. 317,100, dated May 5, 1885.

Application filed May 9, 1884. (No model.)

To all whom it may concern:

Be it known that I, JOHN DENNIS, a citizen of the United States, residing at Glenbeulah, in the county of Sheboygan and State of Wisconsin, have invented a new and useful Combined Wash-Bench and Wringer, of which the following is a specification, reference being had to the accompanying drawings.

This invention has relation to folding wash-benches and clothes-wringers combined; and it consists in the construction and novel arrangement of parts, as will be hereinafter fully described, and particularly pointed out in the claims.

Figure 1 is a view in perspective of a combined wash-bench and clothes-wringer embodying my improvements. Fig. 2 is a plan of the device folded. Fig. 3 is a vertical longitudinal section on the line $\alpha\alpha$, Fig. 1. Fig. 4 is a sectional detail view of the end of the wringer-shaft, the crank-eye, and key for connecting them.

Referring by letter to the accompanying drawings, A A' designate the legs of the wash-bench, which are pivoted together in pairs, one outside the other, to the ends of a shaft, B, provided with ferrules B' at its ends to prevent it from splitting, by screws B'', passed through holes in the legs into holes in the ends 30 of the shaft.

C C designate the side rails of the wash-bench, which are pivoted together at their inner ends by screws, and pivoted also to the upper ends of the legs A A' on their outer 35 faces, and connected by slats D, secured to their upper faces by screws, thereby forming a folding table or wash-bench.

The clothes-wringer that combines with this wash-bench consists of the vertical side rails, E E, bifurcated in their lower ends at F, and passed down between the two slats D D nearest the middle of the wash-bench, and sprung over the ferrules B', and secured in place by threaded eyebolts F', provided with washers 45 F'', and connected together at their upper ends by a top rail, G, secured in the mouths of the vertical slots H H by screws H''. The shafts of the wringer-rollers I and K are made of steel to carry very heavy vulcanized or white 50 rubber rolls, and are much stronger than iron shafts. The shaft I has stationary bearings in the vertical side rails, E E, just below the

lower ends of the vertical slots H H, and its ends project beyond the outer faces of the vertical side rails, E E, and are provided with 55 key-seats a for the key a', which connects the crank-eye b, also provided with a key-seat, b', to the shaft I at either end thereof. The shaft of the upper roller, K, has vertical play in the slots H H beneath spring-pressed blocks 60 L, which are prevented from falling outwardly from the slots by metal guards M, secured to the outer faces of the vertical rails E E.

N designates a steel spring having tenon-shaped ends, which rest on the blocks L in the 65 slots H H. Upon this steel spring N rests a bolster, O, having its upper face plane and its under face convex from end to end. The ends of this bolster also work in the slots H.

The top rail, G, is provided with threaded 70 seats for two thumb-screws, P P, the points of which bear upon the upper face of the bolster, and maintain the pressure of the spring upon the rubber rollers.

On each side of the lower roller, I, parallel 75 with its shaft and about on a line with the top of the shaft, is secured to the edge faces of the vertical side rails, E E, the boards Q Q', provided near each end with a vertical slot, R. Between these two boards Q Q', and projecting 80 from the inner faces of the vertical side rails, E E, are two studs, S, which project through elongated slots T in the arms V of the adjustable water-shelf U. The outer edges of the arms V of the water-shelf U are notched 85 to engage the lower edges of the vertical slots R in the boards Q Q'. These arms may occupy the slots of either board Q or Q', as may be desired, and may be instantly changed from one side to the other. When not in use, the 90 water-shelf hangs down below the boards Q Q'.

When desired, the threaded eyebolts may be withdrawn from the bifurcated lower ends of the vertical rails E E, and the wringer may be removed from the wash-bench, and the latter 95 be converted into a convenient bench or drying-surface for clothing.

The steel shafts will not bend in heavy wringing. The flat steel spring operated by the bolster and thumb-screws keeps the rolls always 100 in true position in all kinds of wringing from a ribbon up to a quilt without changing.

The bench when not in use is simply closed up to the wringer.

The crank, by the use of the key and key-seats, can be quickly applied and removed.

The vertical side rails, E E, are provided with two parallel strips, W, which serve both 5 as strengthening-strips for the wringer-frame and as stops for the two slats D D nearest the middle of the wash-bench when the latter is expanded.

Having thus fully described my invention, 10 what I claim as new, and desire to secure by Letters Patent of the United States, is—

1. The combination, with the side rails, slotted at their upper ends, of the rollers, the upper one of which is vertically movable in said 15 slots, blocks bearing against the upper sides of the ends of the shaft of said rollers, plates M, for retaining said blocks in place, spring n,

having its ends resting on said blocks, a bolster having a convex under face, and having its ends located in the slots of the side rails, 20 and thumb-screws bearing upon the underside of said bolster, substantially as set forth.

2. The combination, with the side rails connected by slotted plates Q, of the slotted arms engaging studs extending inwardly from the 25 side rails, and the shelf U, secured to said arms, as set forth.

In testimony that I claim the foregoing as my own I have hereto affixed my signature in presence of two witnesses.

JOHN DENNIS.
